ATTORNEY

UNITED STATES PATENT OFFICE.

CHARLES GLOVER, OF NEW BRITAIN, CONNECTICUT.

DESIGN FOR A BICYCLE PEDAL MEMBER.

SPECIFICATION forming part of Design No. 29,829, dated December 20, 1898.

Application filed November 2, 1898. Serial No. 695,329. Term of patent 7 years.

To all whom it may concern:

Be it known that I, CHARLES GLOVER, a citizen of the United States, residing at New Britain, Hartford county, Connecticut, have invented and produced a certain new and original Design for a Bicycle Pedal Member, of which the following is a full, clear, and exact description.

My invention relates to a new and original design for a bicycle pedal member.

The accompanying drawings illustrate, in Figure 1, an end elevation, and in Fig. 2 a side elevation, of my new and original design.

This pedal member when viewed in end elevation, as shown in Fig. 1, is in general of

circular form, having its outline varied by inconspicuous projections A A and by the conspicuous projections B B, the said projections B B appearing to be separated at a greater distance from each other than the projections 20 A A.

What I claim is—

The design for a bicycle pedal member substantially as herein shown and described,

Signed at New Britain, Connecticut, this 25
31st day of October, 1898.

CHARLES GLOVER.
